UNITED STATES PATENT OFFICE.

JOSEPH FORSHAW AND NATHAN FORSHAW, OF ST. LOUIS, MISSOURI.

GASOLINE-STOVE ATTACHMENT.

SPECIFICATION forming part of Letters Patent No. 311,182, dated January 27, 1885.

Application filed February 13, 1884. (No model.)

To all whom it may concern:

Be it known that we, JOSEPH FORSHAW and NATHAN FORSHAW, both of the city of St. Louis, in the State of Missouri, have invented

5 a certain new and useful Improvement in Gasoline-Stove Attachments, of which the following is a full, clear, and exact description, reference being had to the accompanying drawings, forming part of this specification, and in

10 which—

Figure 1 is a transverse section of the top of a gasoline-stove, showing the burners, or one of them, in side view, and the device embodying our invention in edge view. Fig. 2 is a front view of the device embodying our invention, showing part of the top of the stove in longitudinal section. Fig. 3 is a vertical section taken on line 3 3, Fig. 1; and Fig. 4 is a similar view to Fig. 2, except that the 15 dial-disk is adjusted to a different position, and the valve is shown closed instead of partly open. Fig. 5 is a detail view showing the slot that receives the bolt that connects our attachment to the stove-top. Fig. 6 represents a 20 modification.

25 Our invention relates to a device to be attached to all kinds of gasoline-stoves; and it consists in features of novelty hereinafter fully described, and pointed out in the claims.

30 Referring to the drawings, A represents the top, and B one of the burners, of an ordinary gasoline-stove.

C represents the stem of the valve, which is bent at D to form a crank or handle, H. 35 The extreme end may be bent to form a loop or eye, I, to give a better hand-hold.

A great deal of difficulty has been experienced in gasoline-stoves by the cranks or levers getting loose upon the valve-stems, but 40 when they are thus formed in one piece this difficulty is entirely avoided, and, besides, a very cheap, strong, and durable article is produced.

J represents a bracket secured to the front 45 edge of the top of the stove by means of a bolt, L, fitting in a hole in the top, and a slot (see Fig. 5) in the bracket. It can thus, with a very little trouble, be attached to any stove, and there may be as many to a stove as there 50 are burners. In the lower part of the bracket is a slot, M, to admit the handle of the valve-stem, and in the lower part of which the stem

fits. The bracket has a shoulder, N, against which the handle of the valve-stem strikes when the burner is fully opened. (See dotted 55 lines, Fig. 3.)

O represents a dial-disk secured to the bracket by a stud, P, entering the slot M, and having a nut on its inner end. The handle of the valve-stem fits between the bracket and 60 disk, as shown in Fig. 1, and its lower end or loop, I, extends slightly beyond the disk, so that it can be conveniently grasped to turn the burner on and off.

Q is a stop-pin on the disk, against which 65 the handle strikes when the valve is closed.

— To compensate for wear on the valve, the disk is made adjustable, so that the stop-pin can be moved farther around, allowing the valve-stem to be turned farther in closing the valve. The 70 disk is made adjustable by a screw, T, passing through it and entering holes U in the bracket. Thus when the stove is new, or when the valve or burners are new, the disk would be in the position shown in Fig. 2, and the valve would 75 be closed when its handle comes against the stop-pin. Then, when the stove had been used for a month, (more or less,) the disk would be moved into the position shown in Fig. 4, thereby raising the stop-pin, allowing the valve- 80 stem to be turned farther, and in this way the valve can always have a stop, and at the same time always be kept tight against its seat.

When the valve becomes still more worn, the disk would be adjusted again by moving the 85 screw T to another hole U. The stud P acts as a pivot upon which the disk turns. The words "open" and "closed" are marked or cast upon the disk, to show which way to turn the valve. 90

As a modification of our preferred form, the bracket J may have perforations J', to receive stop-pins J", as shown in Fig. 6, and then the dial-disk would be left off, the pins filling its office as its mechanical equivalent. 95

We claim as our invention—

1. In a vapor-stove, the combination of a burner, a valve, a valve-stem having a crank-handle, a bracket in front of which the handle rotates, and end stops to indicate the open and closed condition of the valve, and adjustable to compensate for the wear of the valve, as set forth. 100

2. In combination with the burner and valve-

stem of a gasoline-stove, an adjustable dial-disk provided with a stop, substantially as and for the purpose set forth.

3. In a gasoline-stove, the combination of
5 the burner, valve-stem with lever, removable
bracket provided with a slot to receive the le-
ver of the valve-stem, and perforations to re-
ceive the inner end of a screw, and a disk hav-
ing a stud entering the slot of the bracket, and

a screw to enter any one of the perforations of to
the bracket, and having a stop-pin to receive
the lever of the valve-stem when the valve is
closed, as set forth.

JOSEPH FORSHAW.
NATHAN FORSHAW.
